UNITED STATES PATENT OFFICE.

HENRY W. O'DOWD, OF PEEKSKILL, NEW YORK.

GAS-BURNER.

1,175,888.

Specification of Letters Patent. Patented Mar. 14, 1916.

Application filed July 15, 1909. Serial No. 507,673.

To all whom it may concern:

Be it known that I, HENRY W. O'Dowd, a citizen of the United States, and a resident of Peekskill, county of Westchester, and 5 State of New York, have invented certain new and useful Improvements in Gas-Burners, of which the following is a specification.

My invention relates to gas burners of 10 the Bunsen type; and while it may be embodied in gas or vapor burners adopted for various purposes, it is more particularly applicable to burners for stoves and incandescent lamps.

15 Objects of the invention are to provide a burner in which a perfect mixture of gas or vapor and air will be produced; which will permit of the ready and instant regulation of the supplies of gas and air; which will 20 render any possible leakage of gas unobjectionable; and to provide a structure of the character described which will be simple, durable, and cheap in construction and economical in operation. These and other 25 objects of the invention will in part be obvious and in part be made clear from the following description.

The invention consists in the novel parts, 30 improvements, combinations, and features of construction herein shown and described.

The accompanying drawings, which are referred to herein and form a part hereof, illustrate two embodiments of the invention, the same serving in connection with the 35 description herein to explain the principles thereof.

Of the drawings: Figure 1 illustrates an embodiment of the invention, partly in vertical cross-section and partly in perspective; 40 Fig. 2 is a plan view of the same; Fig. 3 is a horizontal sectional view of the same taken on the line 3—3 of Fig. 1; Fig. 4 is a vertical sectional view illustrating another embodiment of the invention; and Fig. 5 is a plan view of the same taken on the line 45 5—5 of Fig. 4.

I have found that the best results can be secured in burners of the Bunsen type by having the gas pass into the air mixing 50 chamber in a compact stream. By employing this character of stream the maximum energy of the gas is utilized in entraining the air. It is impracticable, however, to regulate a burner of this kind without weakening this central stream. The usual man-

ner of controlling such a burner is by employing a needle valve. This, however, increases the stream lines in the orifice so that a large part of the energy of the gas is wasted.

In accordance with my invention I employ a central normally open relatively large orifice of such a size as to supply all the gas required under high pressure conditions. In order to increase the supply of 65 gas under low pressure conditions I provide two or more relatively small auxiliary orifices symmetrically arranged with relation to the central orifice and inclined thereto so that the jets of gas issuing from the 70 auxiliary orifices will combine with the jet issuing from the central orifice, thereby conserving the energy of the gas, means being provided to regulate the supply of gas through the auxiliary orifices.

According to one feature of the invention, means are provided whereby certain of the auxiliary orifices may be regulated independently of the others so that some of the orifices may be shut off while leaving the 80 remaining orifices fully open, the remaining orifices nevertheless being symmetrically arranged with relation to the central jet.

Referring now in detail to the constructions shown in the drawings the embodiment of the invention illustrated in Figs. 1, 2, and 3 comprises a nozzle 1 connected to a gas supply pipe 2, having the ordinary stop cock 4. Extending through the nozzle 1 is a relatively large central orifice 6 and a 90 plurality of relatively small auxiliary orifices inclined toward the axis of the central orifice and symmetrically arranged with relation thereto.

To regulate the flow of gas from the converging orifices a cap 8 is rotatably mounted upon said nozzle 1, said cap having a central orifice and converging orifices in register with the orifices of the nozzle. Preferably and as shown, moreover, the orifices of 95 both the nozzle and cap are disposed in symmetrically arranged sets. The orifices 9, also, of one set are made longer than the orifices 10 of another set, so that the orifices of the cap 8, being of uniform size, 100 while registering as to one set 11 with the extended orifices 9 of the nozzle, will be out of register as to another set 12 with the orifices 10, thus permitting the flow of gas through the orifices 9 and 11 while shutting 110

off the flow of gas through the orifices 10 and 12 simultaneously. The orifices 9 may be extended to any suitable degree and the spaces between the orifices will of course be sufficient to permit one set of orifices in the cap to be out of register with the corresponding orifices of the nozzle while the orifices of another set in the cap are in register with the corresponding and longer orifices of the nozzle.

Another feature of the invention resides in the provision of means for keeping the cap in perfect alinement with the nozzle. While this may be done in various ways, in the embodiment of the invention illustrated in Fig. 1 a screw 13 is provided, the same passing through the nozzle 1 and being screwed into the cap 8, which is tapped for that purpose. On the screw 13 and between its head and the lower inside face of the top of the nozzle 1 is a small spiral spring 14 which acts to keep the cap in perfect alinement. The main central orifice 6 will of course extend through the screw 13. In this embodiment of the invention, also, the top of the nozzle 1 is suitably concaved and the cap 8 correspondingly convexed, which arrangement assists in maintaining the alinement. In this embodiment, moreover, and as shown, the top face of the cap 8 is concaved to correspond with the convexity of the lower face of said cap, the concave space, as shown, including the orifices.

Another feature of the invention resides in providing means for disposing of any gas escaping between the cap and the nozzle. While this may be done in any suitable manner, preferably and as shown, suitable slots 15 are formed in the cap 8 near the top thereof, through which slots the escaping gas is directed into the air current and so brought to the place of combustion.

In an air mixing chamber 17, into which the nozzle and cap protrude, is an air shutter 18, having a series of openings 19 in register with corresponding openings 20 provided preferably, in the base of the air chamber 17 for the admission of air. By means of the downwardly projecting lug 21 the air shutter 18 may be rotated to control the supply of air to the air mixing chamber.

In the embodiment of the invention illustrated in Figs. 4 and 5, which is adapted for use in burners for incandescent lamps is shown another form of the means for regulating the flow of the gas, which means in this particular embodiment takes the form of a plate 23 rotatably mounted on the nozzle 1 by means of a screw 24, whose overlapping head 25 is in alinement with the lower inside face of the top of the nozzle, said screw 23 being engaged at its upper end by a threaded jam nut 26 in alinement with the upper end of the plate 23, said plate 65 being thereby kept in alinement with the

nozzle. The central orifice 6, as in the embodiment of the invention illustrated in Fig. 1, extends through the center of the screw 24. The plate 23 is provided with a plurality of symmetrically arranged converging orifices 27 in register with the orifices of the nozzle, as heretofore explained.

It may be here observed that the converging orifices need not be converged throughout their entire extent provided they converge in the cap sufficiently to make their jets of gas impinge upon the central jet at a suitable point, as heretofore set forth. The orifices in the nozzle may extend in any desired direction, there being shown in the embodiment of the invention illustrated in Fig. 4 orifices 28 extending in a vertical direction and being of a somewhat greater diameter than the corresponding orifices of the plate 23.

While various means may be provided for rotating the plate 23, preferably and as shown, a projecting arm 29 extends downwardly through a slot 30 in the air shutter 31 and a slot 32 in the base 33 of the burner. The air shutter 31 has a plurality of openings 34 in register with corresponding openings 35 in the base through which the supply of air is admitted. The slot 32 in the base is, preferably and as shown, extended so that the rotation of the air shutter 31 may be controlled by either the arm 29 or the lug 21, and it will be readily apparent that the supplies of air and gas may be thus regulated and controlled either simultaneously or independently.

It will be seen that by reason of the construction shown and described a form of gas burner is provided in which a perfect mixture of air and gas and vapor may be produced, and the supply of gas regulated to compensate for variations of pressure and density. Advantages of the invention other than those hereinbefore set forth will be apparent to those skilled in the art.

It is to be understood that my invention in its broader aspects is not limited to the precise construction shown nor to any particular construction by which the invention has been or may be carried into effect, as many changes may be made in the details of the parts without departing from the main principles of the invention and without sacrificing its chief advantages.

I claim:

1. A gas burner comprising a nozzle having a central gas orifice, and a plurality of symmetrically arranged gas orifices so converging upon said central orifice that their jets of gas will impinge upon the central jet to form a compact stream.

2. A gas burner comprising a nozzle having a central gas orifice, and a plurality of sets of symmetrically arranged gas orifices converging upon said central orifice, where-

by the jets of gas from the converging orifices of each set will impinge upon the jet from said central orifice.

3. A gas burner comprising a nozzle having a central gas orifice, a plurality of sets of symmetrically arranged gas orifices converging upon said central orifice, and means for regulating the flow of gas through the orifices of each of said plurality of sets, 10 said means being constructed so as to permit the flow of gas through the orifices of one set while preventing the flow of gas through the orifices of another set.

4. A gas burner comprising a nozzle, a 15 cap rotatably mounted upon said nozzle, a screw connecting said cap and nozzle and having a central orifice extending therethrough, and a plurality of symmetrically arranged orifices extending through said cap 20 and nozzle and converging upon said central orifice.

5. A gas burner comprising a nozzle, a 25 cap rotatably mounted upon said nozzle, a screw connecting said cap and nozzle and having a central orifice extending therethrough, a plurality of symmetrically arranged orifices extending through said cap and nozzle and converging upon said central 30 orifice, and slits in said cap for the passage of escaping gas.

6. A gas burner comprising a nozzle, a 35 cap rotatably mounted upon said nozzle, a screw connecting said cap and nozzle and having a central orifice extending therethrough, a plurality of sets of symmetrically arranged orifices extending through said cap and nozzle and converging upon said central

orifice, and means for regulating the flow of gas through said orifices, said means being arranged so as to permit the flow of gas 40 through the orifices of one set while preventing the flow of gas through the orifices of another set.

7. A gas burner comprising a nozzle with a concaved upper portion, a cap with a correspondingly convexed lower portion rotatably mounted on said nozzle, a screw connecting said cap and nozzle and having a central orifice extending therethrough, and a spring operatively arranged between said 50 nozzle and said screw.

8. A gas burner comprising a nozzle, a cap rotatably mounted upon said nozzle, a screw connecting said cap and nozzle and having a central orifice extending therethrough, a plurality of sets of symmetrically arranged orifices extending through said cap and nozzle and converging upon said 55 central orifice, the orifice of one set in the cap being respectively of greater area than the orifices of another set in said cap, whereby the orifices of one of said sets will be in register with the corresponding orifices in said nozzle, while the orifices of another set in said cap will be out of register with any 60 orifices in said nozzle.

In testimony whereof, I have signed my name to this specification in the presence of two subscribing witnesses.

HENRY W. O'DOWD.
